Inventor
GEORGE FRITZ.

Murray & Zugelton

Attorneys

UNITED STATES PATENT OFFICE.

GEORGE FRITZ, OF CINCINNATI, OHIO.

SECTIONAL BIN.

Application filed September 6, 1924. Serial No. 736,255.

This invention relates to bins such as may be used for storing quantities of stock of various kinds and is especially adapted to provide a bin structure which may be modified from time to time to accommodate the quantity of articles to be stored.

An object of my invention is to provide a bin structure unit which may be mounted with similar units for providing a series of bins of any desired size.

Another object is to provide bins of this nature which may be mounted upon one another without the use of additional fastening means.

Another object is to provide bins of this nature which when mounted upon one another will form practically a single unit of any desired size.

Another object is to provide a structure of this kind from which the individual units may be added or removed with a minimum of effort.

These and other objects are attained by the means described herein and disclosed in the accompanying drawings, in which:

Fig. 1 is a fragmental perspective of a pair of sectional bin units of my invention mounted one upon the other.

Fig. 2 is a cross sectional end view of the device shown in Fig. 1.

The bins of my invention are produced in sectional units 3 which comprise one or several pigeon holes or compartments 4 arranged side by side or one above the other or both. As disclosed in the drawings, each unit comprises ten compartments open on one side only and bounded by the bases 5 and rear walls 6, end walls 7 and partitions 8. The rear wall 6 is provided with an upwardly extending flange 9 against the inner side of which the rear wall 6 of the bin next above may engage. When it is desired to form the sectional units with two tiers of compartments the flange 9 and rear wall 6 of the component parts may be spot welded as at 10. The partitions 8 comprise a flat sheet of metal having flanges 11 extending in a common direction from all four of its sides, the flanges 11 being secured in place by means of spot welding or by rivets. The forward longitudinal edge of the base or bottom 5 of each tier of compartments extends slightly beyond the forward edge of the partitions 8 where it is bent upwardly at substantially right angles at 12 and is then turned inwardly upon itself at a point 13

spaced at a distance from the point 12 and the remainder of the sheet developed into a flattened C-shaped member 14. The top wall 15 of each sectional unit also extends outwardly for a distance beyond the front edge of the partition 8 and is developed into a substantially reversed C-shaped section 16. The C-shaped portion 14 provides a ledge extending along the base of each of the compartments 4 and the outwardly and downwardly turned portions 17 providing spaced flanges for performing the function of a card holder in which an identification card may be retained. The lower flange 17 of the C-shaped member at the base of one unit is adapted to slidably engage the inner walls of the C-shaped member 16 whereby the forward edges of units to be joined upon one another are substantially hooked or secured one upon the other. Coinciding perforations 18 and 19 positioned in the rear wall 6 and the upwardly extending flange 9 respectively are adapted to receive a securing means such as a bolt and nut 20. Thus it will be seen that the forward and rear longitudinal edges of adjoining sections are secured one upon the other as previously described. A series of bins may thus be built up and secured into practically a single unit.

Perforations 21 may be provided in the rear wall 6 for receiving securing means such as nails or screws whereby the sections may be fastened against a wall or whereby a pair of sections placed back to back may be secured one to the other.

What I claim is:

1. In a sectional bin structure the combination of bin units, C-shaped grooved members extending along the lower forward edges of said units, inverted U-shaped groove members extending along the forward upper edges of said units and being formed integral therewith, the upper and lower grooved members of adjacent bins being adapted to slidably interlock one with the other for securing the forward edges of adjacent bins, an offset upwardly extending flange carried by the upper rear edge of one of said bins, said flange being adapted to abut the lower portion of the rear wall of the bin above, and securing means extending through the last mentioned flange and wall.

2. In a device of the class described, the combination with bin units of a grooved card holder extending along the forward lower edge of said units and forming a front

- ledge therefor, a grooved flange extending upwardly from the upper forward edges of the units, a straight flange extending from the upper rear edges of said units, the card holders and grooved flanges of adjacent units being adapted to slidably interlock for securing adjacent bins together along their forward edges, and means for securing the rear flange of one unit to the rear wall of the adjacent unit.
3. In a sectional bin structure, the combination of bin units, C-shaped grooved members extending along the forward lower edges of said units, and inverted U-shaped grooved members extending along the forward upper edges of said units, the upper and lower grooved members of adjacent bins being adapted to slidably interlock one with the other for securing together the forward edges of adjacent bins.
4. In a sectional bin structure, the combination of bin units, C-shaped grooved members extending along the forward lower

edges of said units, inverted U-shaped grooved members extending along the forward upper edges of said units, the upper and lower grooved members of adjacent bins being adapted to slidably interlock one with the other for securing together the forward edges of adjacent bins, and means for securing the bins together at the rear edges thereof.

5. In a sectional bin structure, the combination of bin units, grooved card holder strips extending along the forward, lower edge of each unit and a grooved member extending along the forward, upper edge of each unit, the last mentioned grooved member being adapted to slidably interlock in the card holder of the bin next above, for locking together the forward edges of said bins.

In testimony whereof, I have hereunto subscribed my name this 29th day of August, 1924.

GEORGE FRITZ.
